H. G. HOUGHTON.

RAILROAD TIE,

APPLICATION FILED NOV. 13, 1915.

1,169,159.

Patented Jan. 25, 1916.

H. G. Houghton INVENTOR.

BY *C. F. Bond*

his ATTORNEY.

UNITED STATES PATENT OFFICE.

HORATIO G. HOUGHTON, OF GREEN BAY, WISCONSIN.

RAILROAD-TIE.

1,169,159.

Specification of Letters Patent. Patented Jan. 25, 1916.

Application filed November 18, 1915. Serial No. 61,279.

To all whom it may concern:

Be it known that I, HORATIO G. HOUGHTON, a citizen of the United States of America, residing at Green Bay, in the county of Brown and State of Wisconsin, have invented certain new and useful Improvements in Railroad-Ties, of which the following is a specification, reference being had therein to the accompanying drawing.

10 The invention relates to railroad ties and its principal object consists in the provision of a practically indestructible tie which is adapted to be used with tracks laid in paved roads or streets.

15 A further object consists in constructing a tie where parts subjected to the greatest wear may be easily and conveniently replaced, thus considerably reducing the cost of maintenance.

20 Other objects will become more apparent by reference to the drawings, the specification and the claims forming part thereof.

25 A preferred form of the invention is illustrated in the accompanying drawings in which—

Figure 1 is a perspective view of the tie with one of the rail bed blocks and clamping plates removed. Fig. 2 is a perspective view of the clamping plate. Fig. 3 is a perspective view of a rail bed block. Fig. 4 illustrates a longitudinal sectional view of the assembled tie.

The tie comprises a side member 1 having at its ends flanges 2 extending at right angles thereto and provided with a plurality of apertures. A similar side member 3 is arranged in staggered relation to the side member 1 whose one end projects beyond the corresponding end of its accompanying member while its other end stops short of the corresponding end of the other side member. The side members 1, 3 are formed integrally with the flanges 5 extending at right angles thereto, but in opposite direction to the flanges 2 and 4, respectively. The flanges 5 are in alinement when the side members occupy the working position. Between said side members an oblong rectangular filler block 6 of concrete is provided, whose length is equal to the length of the overlapping portion of the side members 1, 3. The flanges 5 are embedded in the concrete block 6, as is obvious from Fig. 1 of the drawings, whereby the side members are locked in position. The concrete block and the contiguous portions of the side mem-

bers constitute the middle portion of the tie and are of a form similar to the ordinary wooden ties, but have greater durability. A block 7 of fibrous material, such as wood, is placed at each end contiguous to the concrete block 6 and forms an extension thereof. The block 7 contacts on one side with the projecting end of one of the side members and is slightly thicker than the concrete block 6, as is obvious from Fig. 4. These wooden blocks 7 serve as supports for the rails and are adapted to absorb shocks. It is understood that the wooden blocks are treated by the creosote process preparatory to being used as rail beds.

In order to hold the blocks in place angle plates 8 are provided which engage the bed blocks 7 on two sides and abut the flanges of adjacent ends of the side members. One leg of the angle plate extends parallel to the flange of one side member and is provided with a plurality of apertures which register with the apertures in said flange of the side member when the parts are assembled. The other leg of the angle plate 8 is provided with a flange 9 adapted to abut the flange of the other side member and is also provided with a plurality of apertures. Bolts 10 or other suitable fastening means may be inserted in the registering apertures, thus holding the parts of the tie securely together. A base plate 11 is provided which approximately extends over the entire length of the tie structure.

From the foregoing it is evident that the middle portion of the tie structure is practically indestructible and only the blocks constituting the rail bed are subject to wear. These blocks may be easily and conveniently replaced when worn out, as only a small portion of the pavement must be removed in order to permit the replacing of the bed blocks 7.

I am aware that slight modifications and changes may be made in the structural form of the tie or in the arrangement of the parts and I want to avail myself of all such departures which come within the scope of my invention, as indicated in the appended claims.

I claim:

1. A tie comprising a pair of side members each provided with a flange, an elongated block of wear resisting material arranged between said side members, said flanges extending into said elongated block,

- shock absorbing means adapted to form a bed for the rails provided adjacent each end of said elongated block, and means for securely holding the said parts together.
5. 2. A tie comprising a pair of side members arranged in staggered relation to each other, a filler block of concrete provided between said side members and extending between the overlapping portions of said side members, shock absorbing means adapted to form a bed for the rails provided adjacent each end of said filler block and abutting the same, and means for securely holding the said parts together.
10. 3. A tie comprising a pair of side members arranged in staggered relation to each other, a rectangular block of concrete provided between said side members and having a length equal to the length of the overlapping portions of said side members, rail bed blocks composed of fibrous material abutting the ends of said rectangular block and forming extensions thereof, and means for securely holding said parts together.
15. 4. A tie comprising a pair of side members arranged in staggered relation to each other, a rectangular block of concrete provided between said side members and having a length equal to the length of the overlapping portions of said side members, rail bed blocks composed of fibrous material abutting the ends of said rectangular block and forming extensions thereof, and means for securely holding said parts together.
20. 5. A tie comprising a pair of side members arranged in staggered relation to each other, a rectangular block of concrete provided between said side members, rail bed blocks composed of fibrous material abutting the ends of said rectangular block and forming extensions thereof, and angle plates contacting with two sides of said rail bed blocks, said angle plates being secured to adjacent ends of said side members.
25. 6. A tie comprising a pair of side members arranged in staggered relation, a filler block of wear resisting material arranged throughout the overlapping portions of said side members, rail bed blocks of fibrous material forming extensions of said filler block and having a length equal to the length of the projecting portion of said side members, means for interlocking said side members and said filler blocks and means for securely holding the said parts together.
30. In testimony whereof I hereunto affix my signature.

HORATIO G. HOUGHTON.
